UNITED STATES PATENT OFFICE.

GUSTAV MEYERSBERG, OF BERLIN, GERMANY.

APPARATUS FOR THE PRODUCTION OF A GASEOUS OR VAPOROUS FLUID MIXTURE.

No. 895,654.

Specification of Letters Patent.

Patented Aug. 11, 1908.

Application filed August 10, 1906. Serial No. 330,094.

To all whom it may concern:

Be it known that I, GUSTAV MEYERSBERG, engineer, a subject of the Emperor of Austria-Hungary, and a resident of 30 Rankestrasse, Berlin, Germany, have invented certain new and useful Improvements in Apparatus for the Production of Gaseous or Vaporous Fluid Mixtures; and I do hereby declare the following to be a full, clear, and exact description of the invention, such as will enable others skilled in the art to which it appertains to make and use the same, reference being had to the accompanying drawings, and to letters of reference marked thereon, which form a part of this application.

My invention relates to improvements in an apparatus for the production of a gas or vaporous fluid mixture.

For various technical purposes mixtures of gases in the form of vapor and liquids are employed which flow through passages and pipes *e. g.*, in hydraulic compressors or in apparatus, such as hydraulic expanders, in which the energy of flow is brought from that originally existing to a higher value by the expansion of the gas contained in the mixture.

In order to obtain a regular action and one which it is possible to calculate it is convenient to employ the mixture in such a way that liquid and gaseous bodies succeed each other in the passage in which they flow according to a fixed law, *e. g.*, in such a way that a gaseous body of fixed weight always follows a fluid body of fixed weight.

In the accompanying drawings, representing arrangements of apparatus in which such an employment of the flowing mixture can be attained,—Figure 1 is a chordal section showing a portion of the blading of an apparatus constructed in accordance with my invention. Fig. 2 is an axial section through a portion of the complete apparatus. Fig. 3 is a bottom plan view of one form of distributing wheel. Fig. 4 is a diagram illustrating the relative speeds and directions of the rotating wheel and the jets of water passing through it. Fig. 5 is a vertical section through one of the blade passages in the distributing wheel, with a diagram illustrating the relative position of water particles therein. Fig. 6 is a speed diagram corresponding thereto. Fig. 7 is a view similar to Fig. 5 showing the parts in changed relation. Figs. 8 and 9 are views similar to Fig. 3, showing two modified forms of construc-

tion. Fig. 10 is a radial section through the distributing wheel and associated parts of a modified form of apparatus. Fig. 11 is a chordal section through similar parts of another modified form of apparatus. Fig. 12 is a speed diagram corresponding thereto. Fig. 13 is a view similar to Fig. 1, showing the parts differently proportioned. Figs. 14 and 15 are speed diagrams corresponding thereto. Fig. 16 is a radial section through the distributing wheel and associated parts of another modified form of apparatus. Fig. 17 is an axial section through similar parts of still another modified form of apparatus.

a indicates a body constructed after the manner of a turbine wheel and which will be hereinafter referred to as the "distributing wheel"; a portion of the "blading" thereof is shown developed in section in Fig. 1, while Fig. 2 is a transverse section through a portion of the whole apparatus.

The fluid, for example water, flows continuously and uniformly through the distributing wheel, while the wheel rotates with a speed of rotation *u* in the direction of the arrow. The rotation takes place about the axis *x*—*x*. The blading is so arranged that between each two passages *b*, *b* there is a wall *d* of considerable thickness on the outlet side of the distributing wheel, while on the inlet side thereof it is sharpened off. The water flows to the distributing wheel on the inlet side in such a direction and at such a speed that it enters as much as possible without loss by impact, for which purpose there may be employed a fixed guiding apparatus *e* which may be provided with suitable blading. From the distributing wheel the water flows through the passages *b* with an inclination *β* to the relative speed *c*.

Owing to the blade walls *d* being thickened on the outlet side the outlet of the water is not effected as a closed ring, but in separate jets which correspond in cross section to the cross section of the outlets of the passages *b*. In Fig. 3 the wheel *a* is seen from the outlet side. The passages *b* appear in this case as radial slots.

The jets of water flow from the distributing wheel into a system of fixed passages *f*, which are arranged in a circle with their mouths or inlets opposite the distributing wheel. Said system of fixed passages is hereinafter referred to as a guide wheel. As can be seen from Fig. 2 the radial breadth of such passages is such that the jets on entering im-

pinge upon the inner and outer walls of the passages. The passages f are separated from each other by walls g which at the mouths of the passages are so thin that the loss by impact and dispersion of the entering jet upon the faces of the dividing walls is small. At the passage mouths these walls are inclined towards the absolute direction of entry of the jets, so that loss of energy caused by the impact of the liquid on the blades is avoided as much as possible.

The rotating jets from the distributing wheel stream over the mouths of the system of fixed passages. Full or solid jets do not pass into the passages f , but in every case only piston shaped portions thereof, between which portions gas, air or steam flows out of the surrounding spaces h and i . The jets flow from the distributing wheel, as can be seen from the speed diagram—Fig. 4 in which these speeds and directions are separately indicated, with the absolute emergent speed w in their direction of travel into the passages f . In doing so the front and rear faces of the jets retain the direction or inclination of the passage b of the last blade element in the distributing wheel. The reason for this can be seen by reference to Figs. 5, 6 and 7. Fig. 5 indicates the end of one of the blade passages b in the distributing wheel and in Fig. 6 the corresponding speed diagram is shown. 1 and 2 are two water particles of the jet which move along the rear wall of the passage. 1 has just reached the end of the passage, 35 while 2 is assumed to be so far removed therefrom, that the triangle 1, 2, 2¹ is similar to the speed triangle shown in Fig. 6. While the point on the rear wall of the passage upon which the particle 1 stood, moves on in a certain period of time to 2¹, the water particle 1 40 itself has reached the point 1¹ in the chamber adjacent to the outlets of the passages b . All the water particles, which at the commencement lay upon the connecting line between 1 and 2, have moved so far forward during this period of time that at the end of the period they lie upon the connecting line 1¹, 2¹. The rear face of the jet has therefore, after leaving the blade passage b , moved on parallel to itself in the direction w and has retained its inclination β . The same remarks may also be applied to the front face of the jet, with reference to Fig. 7, and as relates to the water particles 3 and 4 which at the end of the 45 period of time reach the points 3¹ and 4¹.

As the inclination of the front and rear faces of the jet is retained it may be concluded that the angle γ which the end faces of the jet (Fig. 1) include with the walls g of the passage, is equal to the angle between the relative and absolute emergent velocity c or w . It is possible therefore to obtain a definite angle of inclination of the end faces of the pistonlike jet portions by selection of the 50 speed diagram. Thus, for example suppose

it is desired that the end faces of the pistonlike jet portions shall be at right angles to the walls g of the passage, then the angle between c and w (Fig. 4) must be made equal to 90°.

Instead of the passages b being of the form shown in Fig. 3 they may have any other desired form, such for example as that shown in Figs. 8 or 9. With passages such as shown in Fig. 8 the end faces of the piston-like 70 water jets will be arched, while with passages such as shown in Fig. 9 the end faces of the piston-like water jets will lie obliquely to the plane in which the apparatus is seen in Fig. 1.

Instead of the fluid flowing through the distributing wheel axially as shown in Fig. 2 it may be caused to flow radially therethrough as shown in Fig. 10. In the arrangement shown in Fig. 10 it is assumed 85 that the liquid flows inwardly from the outside through the guide apparatus e and continues its onward way through the distributing wheel a and fixed passages f which are located in the same plane. Other arrangements are nevertheless possible. Thus for example the flow may take place from the inside to the outside or the radial arrangement may be combined with the axial after the fashion of the "Francis" turbines. Moreover in some constructions the direction of flow may be in a direction between axial and radial, i. e., along a cone.

In some cases it may be of advantage to make the distributing wheel stationary and arrange the passages f to rotate. The blade plan of such an arrangement is indicated in Fig. 11, and the corresponding speed diagram in Fig. 12. In this case separate guide apparatus is omitted, the blading of the stationary 100 distributing wheel a being so constructed as to take the place thereof. The division walls g of the rotating system of passages f are inclined towards the direction of the relative entrant speed indicated by the line 110 c ; in the example shown they lie parallel to the axis of rotation. In this position the passages f may be arranged about a cylindrical surface parallel to its geometrical axis. The inclination of the fluid piston like jet 115 portions to the division walls g is here determined by the angle between the absolute and relative entrant speed w and e .

It may be convenient to allow both the distributing wheel a and the system of passages f to rotate in opposite direction, or to move with different speeds in the same direction.

The rotating part may be driven from the outside of the machine. The resistance 125 which has to be overcome in this instance depends upon the nature of the blading which should be treated according to the same rules as those employed in turbine calculation. According to the selection of the 130

direction of the relative and absolute entrant and emergent velocities of the jet it is possible to insure that the rotating part either opposes a resistance to the driving 5 of the apparatus or exerts a force that assists the drive or one that does not effect the driving at all.

The turning moment of the distributing wheel is obtained, as is well known, from the subtraction of the turning moments which 10 the absolute entrant and emergent velocities produce. If these velocities are equal and both in the same direction, then there is not any total turning moment produced. According 15 as the one or the other velocity preponderates so the wheel either opposes resistance to its rotation or exerts motive force. For practical purposes it is convenient to have a motive moment slightly in 20 excess of that required to turn the wheel and which just balances or counterpoises the resistances as they arise in the usual working number of revolutions. At the proper number 25 of revolutions the wheel then runs round of itself without requiring any assistance from outside and without any acceleration of speed.

The ratios of the blading may be so selected that assuming a definite entrant velocity 30 of the fluid a positive turning moment, that is to say acceleration, will take place below the desired number of revolutions, whereas above this number a negative turning moment, that is to say a braking action will 35 be produced, and, at the proper number of revolutions, the turning moment just counterbalances the rotation resistances. The wheel therefore regulates itself to the correct desired number of revolutions. An example 40 of such construction is shown in Figs. 13, 14 and 15. Fig. 13 shows an axial arrangement of the blading in plan. Fig. 14 shows the speed diagram for the normal number of revolutions and Fig. 15 that for a number 45 of revolutions greater than the normal. Assuming the water flows out of the guide apparatus e into the distributing wheel with the absolute velocity w^1 , at the normal speed of rotation u the relative entrant velocity is c^1 . During 50 the passage through the wheel the relative speed rises from c^1 to the final value c^2 which is obtained by suitably contracting the cross sectional area of the passage. There results an absolute emergent velocity w^2 , the 55 component of which in the direction u is equal to and is in the same direction as the corresponding component of w^1 . The total turning moment is therefore zero. If now, keeping the entrant velocity w^1 the same, the speed of rotation be raised from the value 60 u (Fig. 14) to the value u^1 (Fig. 15) the first result is that on the entry of the water at the speed w^1 a loss of energy takes place by the impact of the water; the impact component 65 is C_s , while the relative entrant velocity after

the impact is c^1_1 ; c^1_1 rises on passing through the passage to c^1_2 , the absolute emergent velocity becoming w^1_2 by the composition of c^1_2 to u^1 . The component of w^1_2 in the direction of u^1 is $A C_1$ (Fig. 15) while the corresponding component of w^1 only attains the value $A B$. The turning moment of the emergent velocity is greater than that of the entrant velocity. A braking action is consequently produced. If the diagram was for apparatus in which the peripheral velocity is less than u , then motive action would be obtained. If therefore water be allowed to flow upon the wheel at rest such wheel will rotate with gradually increasing speed up to 70 the normal number of revolutions and remain at this number of revolutions.

Only the mouths of the passages f turned towards the distributing wheel are shown in the figures. The continuations of these 75 mouths may assume any desired shapes and cross sections, according to the alterations which the mixture is to suffer in them. In the axial arrangement they may be arranged around a cylindrical surface in helical lines or 80 according to the geometrical axes. In the radial arrangement they may lie in one plane. Combinations of both kinds and other shapes are nevertheless possible. An arrangement 85 which enables the formation of rings of fluid to be effected with the omission of the division walls is shown in Fig. 16. This case embodies a radial arrangement with external impact. The system of passages f comprises as many passages as the distributing 90 wheel a . The ends of the passages f are inclined towards the periphery of the circle of the radius r^1 by the amount of the angle δ which is less than 90° . The division t^1 on this periphery is therefore greater than the 95 normal breadth k of the passage k . κ is equal to $t^1 \sin. \delta$. On a circle with the small radius r^2 the division t^2 thereon is equal to k , that is to say $t^2 = t^1 \sin. \delta$ and $r^2 = r^1 \sin. \delta$.

As shown in Fig. 16 the passages f , the breadth k of which remains the same, are arranged round in a gentle curve, so that they lie radially in the case of the inner circle with the radius r^2 . The piston like water jets form in each passage f owing to the 100 equality of their number with the number of the passages in the distributing wheel in the same way. They suffer the same changes in each passage and presupposing that they were formed vertically to the walls g^1 on 105 their entrance and that this vertical position is retained by them owing to the narrowness of the passages during the curvature also they arrive in the same position at the circle of the radius r_2 where they coalesce into 110 a ring. In the case of further flow inward the division walls g^1 may be omitted. Instead of water pistons there have now to be 115 dealt with water rings which are as a whole subjected to the same changes which were 120

otherwise made in the several passages with the several water pistons. Thus, for example, as shown in the axial section Fig. 17, the passages *f* may be so curved that they pass out of the radial into the axial position. It is also possible from the very beginning to employ the axial arrangement even in the distributing wheel, only in this case the inlets into the passages *f* must be arranged upon a circle of a greater radius than the place from which onward the division walls *g*¹ are omitted.

In all cases, instead of the complete impact around the entire periphery hitherto presupposed, partial impact upon a portion of the periphery may take place.

Having thus described my invention, what I claim as new and desire to secure by Letters Patent of the United States of America, 20 is:

1. In an apparatus for producing a mixture of a fluid and a liquid, the combination, with a guide wheel having passages arranged in a circle, of a distributing wheel arranged adjacent to said guide wheel, at least one of said wheels being rotative, said distributing wheel having passages adapted to discharge successive streams of a liquid into the passages of said guide wheel and arranged with 25 their discharge ends at a distance from each other and from the inlet of the passages of the guide wheel, means to supply a liquid to the passages of the distributing wheel, and

means to admit a fluid to the space between the passages of the distributing and guide wheel, the passages of said guide wheel and distributing wheel being arranged at such angles relatively to each other and to the axis of rotation of said rotative member that the energy required for relative rotation of the 35 wheels is imparted to the same by the stream of liquid.

2. In an apparatus for producing a mixture of a fluid and a liquid, the combination, with an inner guide wheel having radially 40 directed passages arranged in a circle, of an outer distributing wheel arranged adjacent to said guide wheel and having radially directed passages adapted to discharge successive streams of a liquid into the passages 45 of said guide wheel and arranged with their discharge ends at a distance from each other and from the inlet of said passages of the guide wheel, means to supply a liquid to the passages of the distributing wheel, means to 50 admit a fluid to the space between the passages of the distributing and guide wheel, and means to rotate said distributing and guide wheel relatively to each other.

In testimony, that I claim the foregoing as 55 my invention, I have signed my name in presence of two subscribing witnesses.

GUSTAV MEYERSBERG.
